Patented Mar. 5, 1918.

UNITED STATES PATENT OFFICE.

WILLIAM D. MARTIN AND HENRY SCHRIK, OF CHICAGO, ILLINOIS.

LATCHING MECHANISM.

1,258,132.

Specification of Letters Patent.

Patented Mar. 5, 1918.

Application filed June 9, 1917. Serial No. 173,718.

To all whom it may concern:

Be it known that we, WILLIAM D. MARTIN and HENRY SCHRIK, both citizens of the United States, and residents of Chicago, in the county of Cook and State of Illinois, have invented new and useful Improvements in Latching Mechanism, of which the following is a specification.

This invention relates to locking mechanism more particularly designed for use in connection with outside doors of ice-intake openings of dwelling houses and apartments.

Among the objects of our invention is to improve the construction of a locking mechanism of the kind referred to, in the several particulars as will hereinafter more fully appear, and to provide in particular a locking mechanism which may be unlocked from the inside of the house or apartment so as to avoid the necessity of the occupant thereof going on the outside thereof for the purpose of unlocking the outer door of the ice-intake opening when a delivery of ice is to be received. A further object of our invention is to so construct the parts of our locking device that the outside door will be automatically locked when closed and thereby avoid the necessity of the occupant of the house or apartment going on the outside thereof in order to lock the outside door after the delivery of ice has been received or to remain about the house for that purpose.

A further object of our invention is to produce a locking mechanism of the kind referred to which will be simple, compact, and inexpensive in construction, and convenient in operation, and may be applied in any ice-intake opening.

The invention consists further in the matters hereinafter described and more particularly pointed out in the appended claims.

In the accompanying drawings—

Figure 1 is a vertical sectional view taken through an ice-intake opening in a building wall, and showing the outer door for closing the opening on the outside of said wall, and an ice-box or refrigerator located at the inner end of said opening; there being also shown, for locking the outer door closed, a locking mechanism constructed in accordance with our invention;

Fig. 2 is a horizontal sectional view taken on line 2—2 of Fig. 1, the ice-box being shown in elevation;

Fig. 3 is a vertical sectional view taken on

line 3—3 of Fig. 2, and showing the parts of our improved locking mechanism in their locking positions;

Fig. 4 is a view of the same parts as shown in Fig. 3, except that the resetting member 60 is shown in the position it occupies when holding the locking end of the latch member out of locking engagement with the keeper;

Fig. 5 is a view showing a portion of the outer door broken away and illustrating the locking mechanism therebehind;

Fig. 6 is a perspective view of the locking end of the latch member; and

Fig. 7 is a perspective view of the swinging end of the lower arm of the resetting member.

In the accompanying drawings, there is shown in detail a locking mechanism constructed in accordance with our invention, 75 and as being applied to the outer door of an ice-intake opening of a dwelling house or apartment. As illustrated, 10 indicates the outside wall of the pantry or kitchen of the house or apartment, and 11 the ice-box 80 or refrigerator located therein. Said wall 10 is provided with a rectangular hole or opening 12 extending transversely therethrough and constituting the ice-intake opening in said wall. Said hole 12 opens at 85 its inner end into a recess or niche 13 provided in the inner face of said wall and in which niche the ice-box 11 is placed with its rear or back wall extending over and completely closing the inner end of said ice-intake opening 12, as shown in Fig. 2. Said ice-box 11 is provided in its rear wall with an ice-receiving opening closed by a door 13, which is hinged along one of its side or vertical edges to the ice-box by hinges (not 95 shown), so that said door in being opened swings outward and into the wall opening 12. The outer end of the wall opening 12 is closed by a door 14, which is hinged along one of its side or vertical edges in such manner as to be swung outward from the wall 10 in being opened. Said door 14 constitutes the outer door of the ice-intake opening 12, and is provided on the outside thereof and adjacent the side edge opposite the hinge 100 means with a handle 15 adapted to be grasped in the opening and closing of said door. For supporting the door 14 in the opening 12, we provide a substantially rectangular metal door frame 16, located at the 105

110

outer end of said wall opening. Said door frame 16 is provided with an inwardly extending, integral flange 17 projecting into the wall opening 12 and completely surrounding the same and bearing flatwise against the top, bottom, and side faces of said wall opening. Said door frame 16 is also provided with an outer marginal flange 18 completely surrounding the same and extending over the outer edges of the wall opening, as shown in Figs. 1 and 2. As shown, said door frame 16 bears against the outer face of the wall 10 about the ice-intake opening 12, and imparts the necessary finish thereto. Said door 14 is hinged to said frame 16 by a hinge rod 19 extending across the inner face of the door adjacent one of the side edges thereof and being secured to said door by clamp straps 20. The ends of said hinge rod project above and below the top and bottom edges of said door and are received in sockets (not shown) in the corresponding portions of the flange 18. Said door frame and hinge means are made as shown in Patent No. 1,224,766, granted May 1st, 1917.

The locking mechanism constituting the subject-matter of our present invention is constructed and applied to the outer door 14 in the following manner: Applied against the rear face of the outer door 14 is a latch casing 21. Said latch casing 21 is located intermediate the upper and lower edges of said door and adjacent the non-hinged or swinging side edge thereof. Said casing is provided with upper and lower flanges 22, 23 having holes 24, through which extend fastening screws or rivets 25 for securing said casing against said door. Said casing 21 is provided in its inner face and between its upper and lower flanges with a longitudinally extending groove 26, which opens through the ends of said casing and when applied against the door 14 is closed along the open side thereby. Located in said groove 26 is a latch member 27, one end of which projects beyond one end of said casing through the open end of said groove. The opposite end of said latch member 27 terminates at the other end of said groove, and is secured to said casing 21 by a pivot pin 28. As shown in Fig. 5, the upper wall of said groove 26 is made straight, that is, parallel to the top and bottom edges of the flanges 22, 23, while the bottom wall of said groove is inclined downwardly from the pivoted end of the latch member. Thus the width of the groove 26 at the pivoted end of the latch member 27 is less than the width of the groove at the opposite end of the latch member, thereby permitting the outer or free end of said latch member 27 to be raised and lowered for engagement with a keeper 29, to be presently described. The 65 swinging or outer end of said latch member

27 is provided with a locking head 30 arranged at substantially right-angles thereto and projecting inwardly from the rear face of said outer door 14, when the parts are applied thereto, as shown in Fig. 3. The upper wall of the groove 26 constitutes, in effect, a stop-member for preventing the latch member 27 from being raised or swung upward too far to permit the latch member to drop by gravity or its own weight against the lower edge of said groove, while the latter acts as a stop-member preventing the latch member 27 from dropping below a position preventing the locking head of the latch member from engaging the keeper, 80 when the outer door is swung closed.

The keeper 29 is located in the wall opening 12, and is secured to the side face thereof adjacent the swinging side edge of the outer door 14. As shown, said keeper has the form of a casing having upper and lower flanges 31, 32, through which extend rivets or fastening screws 33, 33 for securing said casing in the wall opening. In the instance shown, the keeper is secured to the inwardly extending flange 17 of the door frame 16. Said keeper casing is provided with a chamber 34 closed along its open side by the flange 17, when the keeper is secured thereto. The end of the chamber away from the door 14 is closed by an end wall 35, as shown in Figs. 3 and 4. The opposite end of the chamber is open so as to receive therein the locking head 30 of the latch member 27. The open end of said chamber 34 is provided with an upright flange 36, with which the locking head 30 is adapted to be engaged for locking the outer door 14 closed. As shown in Figs. 3, 4, and 6, the locking head 30 is provided with a locking shoulder 37, which engages behind the flange 36, when the outer door is locked closed by the latch member 27. The lower edge of the locking head 30 and the upper edge of the flange 36 are both inclined or beveled in the proper directions, so that the locking head will readily ride over and drop behind the flange 36 when the door is swung closed. As is apparent, when the door 14 is open, the latch member 27 rests against the lower edge of the slot 26, and its locking head 30 is in position to engage with and ride over the upper edge of the flange 36 when the door is swung into its closed position. In riding over the flange 36, the locking end of the latch member is raised or swung upward, as is apparent, and, as soon as the edge of the flange 36 is cleared, drops by gravity behind the flange and is retained by its own weight in such position, thereby locking the door 14 closed.

In order to unlock the latch member 27 from the inside of the house or, in short, from the ice-box side of said wall 10, we provide a resetting member 38, which, as

shown, is located in the chamber 34 and is of the bell-crank lever type. Said lever 38 is mounted in said chamber on a pivot pin 39, and the lower arm 40 of said lever is the 5 longer arm thereof and has its free or swinging end in position to be raised upward against the locking head 30, when the latter is interlocked with the keeper. The short arm 41 of said lever extends upward and has 10 secured thereto one end of a pull rod or cable 42, the latter extending through a hole or aperture 43 in the end wall 35 of the keeper casing, as shown in Figs. 3 and 4. Said cable 42 extends to the front side of the 15 ice-box 11, and is provided at such end with a finger-piece or handle 44, which may be grasped when operating the lever 38 for unlocking the latch 27. When the lever arm 40 is swung upward, its free or swinging end 20 engages beneath the locking head 30 and raises the same out of locking engagement with the flange 36. Thereupon the outer door is unlocked and may be swung open from the outside of the wall 10. To hold 25 the latch 27 in unlocked position while the outer door remains closed, the locking head 30 is provided with an outwardly projecting portion or nose 45, on each side of which is an angularly arranged flat shoulder or 30 surface 46, 46, as best shown in Fig. 6. The outer or swinging end of the lever arm 40 is provided with an upwardly opening groove 47, the bottom wall 48 of which is inclined downwardly toward the open end of said 35 groove. When the lever arm 40 is raised or swung upward, the projection or nose 45 is received in the groove 47, and the bottom wall thereof coming into contact with the lower inclined face of the locking head acts 40 to raise or swing the locking end of the latch upward and out of locking engagement with the flange 36. The end faces of the portions of the lever arm 40 on each side of the groove 47 are made flat, and are 45 adapted to bear flatwise against the shoulders 46, 46. When such parts are brought into complete engagement, the swinging end of the lever arm 40 bears at substantially right-angles against the shoulders 46, 46, 50 and the weight of the latch member 27 on the lever arm 40 serves to maintain such parts in such positions and holds the latch member raised while the outer door 14 remains closed. As soon as said door is swung 55 open, the locking head 30 is carried with the door away from the end of the lever arm 40, and the latter drops by its own weight into its normal position, as shown in Fig. 3. When the outer door 14 is again closed, the 60 locking end 30 of the latch member 27 rides over and becomes locked with the flange 36, thereby locking the door closed. This operation is automatic. To reset the latch so that the door may be again opened, the cable 65 44 is pulled, and the lever 38 operates to

raise and hold the locking end 30 of the latch out of locking engagement with the keeper 29.

With our locking mechanism installed, the many advantages incident thereto are apparent. The outer door of the ice-intake opening may be unlocked from the inside of the house, thereby avoiding the necessity of the occupant of the house going on the outside thereof in order to unlock said outer door, when a delivery of ice is about to be received. Then again, after unlocking the outer door, the occupant of the house may leave the same with the assurance that the outer door will be automatically locked when 70 closed after the ice delivery has been received and placed in the ice-box. Then again, all of the locking mechanism is located behind the door and concealed from view thereby, thus having the effect of a secret lock. Furthermore, the operative parts of our lock are housed within casings, thereby preventing the lock from being picked or otherwise tampered with from the outside of the door, when the latter is closed 75 and locked. Moreover, the parts are simple in construction and arrangement and devoid of any sensitive parts such as springs and the like. Then again, the lock as a unit is complete in itself, and may be readily and 80 easily applied to any ice-intake opening. While we have shown a door frame for the outer door, yet it is to be of course understood that such showing has been made more with the idea of illustrating our invention 85 than confining the same to the particular type of door frame and door shown, as it is manifest that our locking device may be applied to any ice-intake opening whether having a door and door frame as herein described or not. 90

To prevent the outer door 14 from being blown or accidentally jarred open while the latch member 27 is held in its unlocking position by the resetting lever 38, the keeper 110 flange 36 is provided at its upper edge with an inwardly facing, rounded shoulder 47, with which the lower rounded edge of the locking head 30 frictionally engages. Thus, the locking head 30, although in unlocking 115 position, still engages the keeper and serves to hold the outer door from being blown open by the wind or being accidentally jarred open. Consequently, a sufficient outward pull on the door 14 is required to open 120 the same.

Furthermore, it is to be of course understood that the details of construction and arrangement of parts illustrated may be variously changed and modified without departing from the spirit and scope of our invention, and that we do not wish to be limited to the details of construction and arrangement of parts shown, except as pointed out in the appended claims. 125

We claim as our invention:

1. In combination, a door, a keeper, a latch member mounted on said door and adapted to have locking engagement with said keeper for locking said door closed, a resetting member adapted when moved in one direction to engage said latch member and move and hold the same out of locking engagement with said keeper while said door remains closed, and said resetting member moving, upon the opening of said door, into a position permitting said latch member to move into locking engagement with said keeper when the door is again closed, and means for operating said resetting member.
2. In combination, a door, a keeper, a latch member pivotally mounted on said door and adapted to have locking engagement with said keeper for locking said door closed, a resetting member pivotally mounted on said keeper and adapted when moved in one direction to engage said latch member and move and hold the same out of locking engagement with said keeper while said door remains closed, and said resetting member moving, upon the opening of said door, into a position permitting said latch member to move into locking engagement with said keeper when the door is again closed, and means for operating said resetting member.
3. In combination, a door, a keeper, a latch member pivotally mounted on said door and adapted to move by its own weight into locking engagement with said keeper for locking said door closed, a resetting member pivotally mounted on said keeper and adapted when moved in one direction to engage said latch member and move and hold the same out of locking engagement with said keeper while said door remains closed, and said resetting member, upon the opening of said door, moving by its own weight into a position permitting said latch member to move into locking engagement with said keeper when the door is again closed, and means for operating said resetting member.
4. A locking mechanism of the character described, comprising a keeper, a movably mounted latch member adapted to have locking engagement with said keeper, a movably mounted resetting member adapted when moved in one direction to engage said latch member and move the same out of locking engagement with said keeper, said latch member when engaged with said resetting member exerting a pressure on the latter in such a direction that the resetting member will be maintained in a position holding said latch member out of locking engagement with said keeper, and means for moving said resetting member into engagement with said latch member.

5. A locking mechanism of the character described, comprising a keeper, a pivotally mounted latch member adapted to move by its own weight into locking engagement with said keeper, a resetting member pivotally mounted on said keeper and adapted when moved in one direction to engage said latch member and raise the same out of locking engagement with said keeper, said latch member and said keeper being provided with parts adapted when engaged to permit the weight of the latch member to be exerted on the resetting member in such a direction that the latter will be maintained in a position holding the latch member out of locking engagement with said keeper, and means for moving said resetting member into engagement with said latch member.

6. A locking mechanism of the character described, comprising a keeper, a pivotally mounted latch member adapted to have locking engagement with said keeper, a bell-crank lever pivotally mounted on said keeper and having an arm adapted to be moved into engagement with said latch member and move the same out of locking engagement with said keeper, said latch member when engaged with said arm exerting a pressure thereon in such a direction that said arm will be maintained in a position holding said latch member out of locking engagement with said keeper, and means for moving said lever into engagement with said latch member.

7. A locking device of the character described, comprising a keeper, a latch member, an arm pivotally mounted at one end and having its other end in position to engage the locking end of said latch member, and means for operating said arm so that the swinging end thereof will engage the locking end of said latch member and move the same out of locking engagement with said keeper; the locking end of said latch member and the swinging end of said arm being provided with flat parts adapted, when engaged, to permit the weight of said latch member to be so exerted on said arm that the latter will be held raised and serve to hold the latch member out of locking engagement with said keeper.

8. A locking mechanism of the character described, comprising a keeper, a latch member having a locking head adapted to have locking engagement with said keeper, a bell-crank lever pivotally mounted on said keeper, one arm of said lever having its swinging end in position to engage said locking head and move the same out of locking engagement with said keeper, and means for operating said lever, said locking head being provided with a projection and having flat shoulders on each side thereof; the swinging end of said arm being provided with a groove adapted to receive said

projection, and the end of said arm being provided with flat faces adapted to engage said shoulders.

9. A locking mechanism of the character described, comprising a keeper, a latch casing having a groove therein and opening endwise through one end of said casing, a latch member pivotally mounted in said groove and having its locking end projecting outwardly through the open end thereof, a resetting member mounted on said keeper and adapted, when operated, to move and hold the locking end of said latch member out of locking engagement with said keeper, and a pull cable for operating said resetting member.

10. A locking mechanism of the character described, comprising a keeper casing having a chamber therein, a latch member having a locking head adapted to enter said chamber and have locking engagement with one of the walls thereof, a bell-crank lever pivotally mounted in said chamber and having an arm adapted to engage said locking head and move and hold the same out of locking engagement with said keeper casing, and a pull cable extending through one

of the walls of said chamber and connected with said lever.

11. The combination of a door, a keeper, 30 a latch member pivotally mounted on the door and adapted to have locking engagement with said keeper for holding said door closed, a resetting member mounted on the keeper and adapted when operated to move 35 and hold the latch member out of locking engagement with said keeper, means for operating said resetting member, and said latch member and said keeper being provided with parts adapted to frictionally engage while the latch member is held in its unlocking position, so as to prevent the door from being blown or accidentally jarred open.

In testimony that we claim the foregoing 45 as our invention, we affix our signatures in the presence of two witnesses, this 29th day of May, A. D. 1917.
